H. L. UNLAND

ELECTRIC BOILER

Filed Nov. 22, 1923

Inventor:
Harry L. Unland,
by *Myron L. Lantz*,
His Attorney.

Patented Jan. 6, 1925.

UNITED STATES PATENT OFFICE.

HARRY L. UNLAND, OF SCHENECTADY, NEW YORK, ASSIGNOR TO GENERAL ELECTRIC COMPANY, A CORPORATION OF NEW YORK.

ELECTRIC BOILER.

Application filed November 22, 1923. Serial No. 676,423.

To all whom it may concern:

Be it known that I, HARRY L. UNLAND, a citizen of the United States, residing at Schenectady, in the county of Schenectady, State of New York, have invented certain new and useful Improvements in Electric Boilers, of which the following is a specification.

The present invention relates to electric boilers, and particularly electric boilers of the electrode type wherein steam is generated by the passage of alternating current through water, although it is not necessarily limited thereto.

For certain applications, the condition is met with where a small amount of steam is required continuously and where for brief intervals a comparatively large amount is required. For example, in connection with steam turbines it may be desirable to keep a turbo-generator set operating continuously at practically no load in order to have it warmed up and running ready to assume a load in case of some emergency. In such a case it is necessary, of course, to have available a supply of steam for operating the turbine which supply is of sufficient volume to carry the emergency load, and the object of my invention is to provide an electric boiler particularly adapted for use under these operating conditions.

For a consideration of what I believe to be novel in my invention, attention is directed to the accompanying description and the claims appended thereto.

In the drawing, the figure is a diagrammatic view of an electric boiler embodying my invention.

According to my invention, I provide an electric boiler comprising a drum 1 which contains a supply of water 2, and a shell 3 directly adjacent the drum and containing the electric heating elements 4. In the present instance the electric heating elements 4 are in the form of electrodes carried by supporting conductors 5 which project through insulators 6 to the outside of the shell. Three electrodes are shown which adapt the boiler for connection to a source of three-phase alternating current. The lower end of electrode shell 3 is connected to drum 1 by a number of openings 7 and also by a conduit 8 controlled by a valve 9 having an operating handle 10 located outside of drum 1 so that valve 9 may

be adjusted at any time. At 11 is a pump which may be driven in any suitable manner and which draws water from drum 1 through a conduit 12 and delivers it to shell 3 through a conduit 13. Conduit 13 has two branches 14 and 15 each provided with a regulating valve 16. By adjusting valves 16 and also valve 9 the rapidity of the circulation of the water from drum 1 to shell 3 may be regulated. The upper portion of drum 1 and shell 3 which are steam spaces are connected by conduits 17 and 18 to a conduit 19 which conveys steam to the point of consumption.

Arranged in conduit 19 is a pressure reducing valve 20 which is set to effect a substantial reduction of pressure in the steam flowing through it so that it maintains on its inlet side, that is, in drum 1 and shell 3 a pressure substantially higher than is applied to the point of consumption, for example, the steam turbine inlet. This means, therefore, that there is a substantial difference in pressure between the steam generated and that applied to the turbine inlet or other consumption point. Valve 20 may be of any suitable structure. In the present instance, a known type is indicated, the amount which the valve is opened being under the influence of the pressure on the discharge side of the valve so as to maintain such pressure substantially constant, as is well understood. With such a valve, when the pressure on the low pressure side decreases due to an increase in the demand for steam the valve is automatically opened further while when such pressure increases, the valve will be moved toward closed position. In conduit 19 I provide also preferably, a non-return valve 21 which may be of any suitable structure and serves to prevent flow from conduit 19 back toward the boiler. 22 indicates a conduit through which make-up water may be supplied to the boiler.

In operation, pump 11 continuously circulates water from drum 1 through pipes 12 and 13 to shell 3 from whence it runs back to drum 1 through openings 7 and conduit 8; and the pump and valve 9 are so regulated as to give the desired circulation of water and maintain the desired level of water in shell 3 which forms the electrode chamber. In a boiler of the electrode type, the input to the boiler depends upon the

depth to which the electrodes are submerged, as is well understood, and the regulation is made such that the electrodes will be submerged to such a depth as to generate sufficient steam to supply the normal minimum requirements at the point of consumption, for example, in the case of a steam turbine to keep the turbine operating idle, and in addition charge and keep charged with heat the water in drum 1. Drum 1 is in communication with the steam space in electrode shell 3 through pipes 17 and 18 so that the pressure in drum 1 is the same as that of the steam being generated, and the circulation of the water from drum 1 to the electrode shell 3 is maintained sufficiently rapid so that the water in drum 1 will be maintained at substantially the same temperature as that in shell 3, i. e., at the temperature corresponding to the temperature of saturated steam at the pressure in the boiler.

As stated above, the electric boiler generates sufficient steam to supply the normal requirements to the point of consumption. In case of a sudden large demand, the pressure on the discharge side of the reducing valve 20 will decrease which results in a further opening of valve 20 and a more rapid flow of steam through it and hence a reduction of the pressure in drum 1 and shell 3. When this reduction in pressure occurs, water in the drum and shell will immediately flash into steam and furnish to the point of consumption a volume of steam to supply temporarily the increased demand.

In substance, the water in drum 1 acts as a heat storage medium in which heat from the electric boiler is stored and which is capable of giving up its heat in the form of steam upon a reduction of the pressure in the boiler.

The capacities of electrode shell 3 and

heat storage drum 1 may be made such as to meet the operating conditions met with in any particular instance. The arrangement finds especial utility however, where the normal requirements are comparatively small as compared to the occasional or emergency demand, and the emergency demand occurs but seldom, for under these circumstances the electric boiler need be only large enough to meet the normal demand for steam and to recharge the heat storage drum 1 within a specified time.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is,—

1. In combination, an electric boiler comprising a shell, electric heating elements in the shell and a heat storage drum in direct communication with the shell, means for circulating liquid from the drum to the shell, a discharge conduit which leads to a point of consumption, and a reducing valve in said conduit.

2. In combination, an electric boiler comprising a shell of smaller capacity and a heat storage drum of larger capacity, electrodes in said shell, means for circulating liquid from the drum to the shell and back to the drum, means for regulating the circulation, a discharge conduit in communication with both the shell and drum, and a reducing valve in said conduit.

In witness whereof, I have hereunto set my hand this 21st day of November, 1923.

HARRY L. UNLAND.
